UNITED STATES PATENT OFFICE.

STANLEY M. UDALL, OF BUFFALO, NEW YORK.

AERO-ENGINE CONTROL.

Specification of Letters Patent Patented June 29, 1920.

1,345,037.

Application filed January 21, 1918 Serial No. 912,930

To all whom it may concern:

Be it known that I, STANLEY M. UDALL, a citizen of the United States, residing at Buffalo, in the county of Erie and State of New York, have invented a new and useful 5 Aero-Engine Control, of which the following is a specification.

This invention relates to means for automatically changing the effective leverage of 10 the throttle operating means of carburetors for internal combustion engines of flying machines, and its object is to provide means for causing the throttle to move through greater arcs as the pressure of the surrounding air changes so that as the atmospheric pressure falls, the throttle opening increases, the movement of the manually 15 actuated member remaining constant.

As the power of an engine VARIES within 20 wide limits substantially with the amount of the charge, (other factors remaining the same) means for increasing the throttle opening for equal movements of the throttle actuator according as the air pressure decreases will cause the engine to generate substantially equal power for predetermined 25 movements of the throttle actuator for substantially all altitudes.

The invention consists in a throttle actuating lever and a link connected thereto, and a automatic means for increasing the distance of the connecting point of said link from the fulcrum of the lever as the air pressure decreases.

In the accompanying drawing, Figure 1 is a central vertical section of this improved controlling mechanism. Fig. 2 is a longitudinal section of the pump therefor. Fig. 3 is an elevation taken from the right in Fig. 1, of the actuating handle for the throttle of the carburetor. Fig. 4 is transverse section of the hand lever through the pin C.

Similar reference characters refer to like parts throughout the several views.

The carburetor is not shown in the drawings and only one end of the link R connecting to the throttle thereof is indicated, as the carburetor forms no part of this present invention. A hand lever or operating member A is hollow and in it is slidably a rod or controlling member B to which a link or actuating member R is connected by means of the pin C. The hand lever is preferably formed with slots Z to permit the pin C to move freely. This lever is integral

with the cylinder D in which slides the piston E, normally held toward the hand lever by means of a spring S. The handle is provided with a hollow fulcrum F which is rotatable in the bearing G and held therein by 60 means of a spring I and collar U. The position of the piston E and rod B controls the leverage of the link R.

An air pipe connects to the bearing G by means of a nut B and to a pump cylinder M 65 by means of a nipple N and nut O. Within the cylinder is a piston P which has a rod Y held in engagement with the valve X by means of a spring W. When the piston is at the inward end of its stroke, it uncovers the ports 1, which may communicate with the atmosphere through the pipe T.

When the piston is at the outward end of its stroke the projection X thereon contacts the valve Y and lifts it from its seat.

Operation: When flying in low altitude the air which rushes into the cylinder M through the holes 1 will be compressed and forced into the cylinder D through the pipe Q and through holes in the hollow fulcrum F until a certain pressure is stored therein which forces the piston E away from the bearing G until the pin C is at the position C' in Fig. 3. At this point, the pressure within the cylinder D and the final pressure within the cylinder M will be balanced for that particular altitude because the valve Y is lifted at the end of each stroke of the piston P and equalizes these pressures. The effective leverage of the hand lever A is therefore the distance between the fulcrum 85 F and the fulcrum A (Fig. 3) and the fulcrum. At another altitude, the air being rarer, the final pressures being less, the pin C will become stationary at C'', and at a still higher altitude at C'''. In 95 other words, the piston E under pressure of the spring on one side and under pressure of air on the other will come to a rest at one certain position for each atmospheric pressure, and the distance between the pin C and 100 the fulcrum F will depend upon this pressure.

If now the aviator is accustomed at certain altitudes to swing his lever A through the arc indicated by the broken lines 1 and 2 in Fig. 3 to obtain a certain speed of his engine, he will also obtain this speed at all other altitudes because at higher altitudes this movement will cause a movement of the link R (indicated by dotted lines R', R'') 110

and R'') and thus an opening of the throttle in inverse ratio to the air pressure.

A secondary and incidental result obtained is that the carburetor to which this control may be fitted may be so adjusted that as the throttle is opened wider at higher altitudes the mixture is maintained sufficiently nearly constant that the engine develops its full power and if the machine 10 dives from a high altitude to a lower altitude the automatic closure of the throttle will maintain the mixture sufficiently rich at low altitudes to prevent a back-fire.

This closure also tends to prevent the engine speeding up excessively under such circumstances, which seriously overstresses an engine. The dynamic pressure of the air when the machine dives is utilized to effect the closure.

20 I claim:—

1. The combination of an operating hand lever, a rod slidably mounted therein, a piston connected to said rod and a cylinder connected to said hand lever in which cylinder the piston is slidably, an air pump and a pipe connecting said pump and said cylinder, a spring to act on the cylinder against the pressure caused by the pump, and means to cause the pressure in the cylinder and the 30 pump to equalize.

2. The combination of an operating member and a link having an adjustable connection therewith, a piston connected to both the operating member and the link, and 35 means for positioning the piston according to the pressure of the surrounding atmosphere, and thereby the relative positions of the link.

3. The combination with an air pump and a cylinder to receive the air therefrom, the pump connecting alternately and positively to the outside atmosphere and to the cylinder at each cycle of its operation, a piston in said cylinder, a spring to resist the action of air pressure on the piston, and a controlling device attached to said piston. 40

4. The combination of an air pump and an air cylinder, means to control the action of the air pump so that the pressure within the cylinder shall always have a fixed relation to the pressure of the atmosphere, a hand lever and means operated by said hand lever through arcs whose radii are determined by said pressure. 50

5. The combination of a pivoted operating hand lever and a cylinder connected thereto, a fulcrum for the handle, a rod slidable in the hand lever and a piston connected to the rod slidable in the cylinder, a spring in the outer end of the cylinder to normally hold the piston toward the fulcrum of the handle, a link connected to the rod, an air pump comprising a cylinder, piston and discharge valve, and a pipe leading from the pump to the fulcrum of the 65 operating hand lever which is provided with a passage to the cylinder connected to the hand lever, said pump cylinder having openings to admit air at the end of the suction stroke of the piston and said piston 70 having a projection to lift the discharge valve off its seat at the end of each compression stroke so that the pressure in the two cylinders will always be equal at each lifting of said valve.

STANLEY M. UDALE.
